UNITED STATES PATENT OFFICE

THOMAS J. WEAVER, OF PROVO, UTAH

NOZZLE SUPPORT AND SPRAY

Application filed October 16, 1928. Serial No. 312,797.

The invention relates to combined nozzle supports and sprays, for instance for conventional garden hose, and has for its object to provide a device of this character comprising a head adapted to be received on the end of the hose, which head is provided with a downwardly extending stake adapted to be driven into the ground as a support, and a deflecting member vertically adjustable on the stake and adapted to be placed in various positions in relation to a discharge nozzle carried by the head for deflecting and spraying liquid discharged from the nozzle.

15 A further object is to imbed the upper end of the stake in the head during the molding operation for securely anchoring the head on the stake.

20 A further object is to form the deflecting member from a single piece of sheet material bent to form a sleeve through which the stake extends and a deflecting member extending angularly upwardly and terminating forwardly of the discharge nozzle.

25 A further object is to form the deflecting member from a single piece of material, the opposite sides of which are bent inwardly to positions for forming opposite sides of the sleeve in parallel relation and the corners bent inwardly to form triangularly shaped members overlying the rear side of the stake for forming the rear side of the sleeve and to secure said triangular shaped members together for forming the sleeve frictionally engaging the stake. Also to provide lugs on opposite sides of the sleeve, preferably formed from solder and acting as securing means for the triangularly shaped members and finger engaging means for adjusting the sleeve upwardly and downwardly in relation to the discharge nozzle.

35 With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the

In the drawing:—

Figure 1 is a perspective view of a portion of a hose showing the device applied thereto.

Figure 2 is a vertical longitudinal sectional view through the head and deflecting member.

Figure 3 is a perspective of the deflecting member.

Figure 4 is a vertical transverse sectional view through the head taken on line 4—4 of Figure 2.

Figure 5 is a plan view of the blank from which the deflector is formed.

Referring to the drawing the numeral 1 designates the end of a conventional form of hose of the garden type and 2 the nozzle head threaded thereon. The nozzle head 2 is provided with a downwardly extending stake 3, the upper end of which is provided with a bifurcation 4 in which is disposed the tubular discharge nozzle 5. In the course of manufacture the stake and nozzle 5 are placed in engagement with each other, and after which the head 2 is cast around the same, thereby materially reducing the cost of manufacture. The lower end of the stake 3 is provided with a point 6 so the same may be easily forced into the ground for supporting the nozzle and hose end.

Slidably mounted on the stake 3 and adjustable towards and away from the discharge end of the nozzle 5 is a deflecting plate 7, which inclines upwardly and outwardly in relation to the nozzle 5 and deflects in a stream or spray, liquid projected against the same under pressure from the nozzle 5, thereby distributing in a sheet or spray liquid over a relatively wide area, for instance a lawn. By adjustably mounting the deflecting plate on the stake 3 it is obvious that it may be adjusted in relation to the discharge end of the nozzle 5 for varying the water deflection according to the lawn area desired to be covered. The deflecting member 7 is provided with a sleeve 8 in which the stake 3 frictionally engages and the sleeve 8 as well as the deflecting member 7 is formed from a single sheet of metal as shown in Figure 5. The sheet 7 is

first bent on the dotted lines 9 so that the triangular portions 10 will engage the face of the sheet, after which the corners are bent outwardly on the lines 11 which will be in parallel relation for forming the side walls 12 of the sleeve 8, which walls will also be in parallel relation as shown in Figure 3.

After the forming of the side walls 12, the corner members 13 are bent inwardly towards each other on the lines 14, thereby forming triangular shaped members which overlie the rear side of the stake 3 and finally the device so formed is bent at 15 and 16 to incline the deflecting member 7 upwardly and outwardly, as clearly shown in Figure 2, however it will be seen that the upper portions of the members 10 will rigidly brace the deflecting member, and at the same time if so desired the angularity of the deflecting member 7 may be varied by further bending on the lines 16. After forming the deflecting member shown in Figure 3, the stake 13 is forced through the sleeve 8, which sleeve frictionally engages the stake, and then the triangular members 13 are preferably connected together by a drop of solder 17, which not only secures the members 13 together but forms a finger engaging member adapted to be grasped by the operator for adjusting the deflecting member to various positions on the stake. If so desired a second drop of solder 18 may be placed on the front side of the sleeve to act as a finger engaging member for adjusting the deflector, however this may be eliminated if desired. A drop of solder 17 is not shown in Figure 3 but in dotted lines in Figure 1 for purposes of clarity.

From the above it will be seen that a spraying and deflecting device is provided which is slidably mounted on a stake whereby it may be adjusted to various positions in relation to a discharge nozzle and said stake not only supports the discharge nozzle but also the deflecting member. It will also be seen that the deflecting member and its sleeve are formed from a single piece of sheet metal bent to form, thereby allowing the same to be cheaply manufactured and sold.

The invention having been set forth what is claimed as new and useful is:

1. The combination with a discharge nozzle having a discharge port, a stake carried by said nozzle at an angle to said discharge port, of a deflecting member forwardly of the nozzle, said deflecting member being adjustably mounted on the stake, whereby it may be adjusted transversely in relation to the axis of the discharge nozzle.

2. The combination with a discharge nozzle, a downwardly extending stake carried by said discharge nozzle, of a deflecting plate, said deflecting plate being adjustably

mounted on the stake and adjustable transversely in relation to the nozzle and inclining upwardly and outwardly and terminating forwardly of the nozzle.

3. The combination with a nozzle, a supporting stake carried by said nozzle at an angle to the axis of the nozzle, of a deflecting plate, said plate inclining upwardly and outwardly and terminating forwardly of the nozzle, a sleeve carried by said plate, said sleeve being vertically adjustable on the stake toward and away from the axis of the nozzle.

4. The combination with a nozzle, an angularly disposed stake carried by said nozzle, of a water deflecting plate, said plate being disposed to one side of the nozzle and inclining upwardly and outwardly and terminating forwardly of the nozzle, a sleeve carried by said plate, said sleeve being frictionally held in various positions on the stake at different distances in relation to the nozzle.

In testimony whereof I hereunto affix my signature.

THOMAS J. WEAVER.
